UNITED STATES PATENT OFFICE.

FREDERICK W. SHEE, OF LANCASTER, PENNSYLVANIA, ASSIGNOR OF ONE-HALF TO
RALPH P. WILTON, OF WRIGHTSVILLE, PENNSYLVANIA.

DESIGN FOR A RECEPTACLE FOR DISPENSING DRINKING-STRAWS.

41,859.

Specification for Design.

Patented Oct. 24, 1911.

Application filed August 11, 1911. Serial No. 643,623. Term of patent 14 years.

To all whom it may concern:

Be it known that I, FREDERICK W. SHEE, a citizen of the United States, residing at Lancaster, in the county of Lancaster and State of Pennsylvania, have invented a new, original, and ornamental Design for Receptacles for Dispensing Drinking-Straws, of which the following is a specification, reference being had to the accompanying drawing, forming part thereof.

The figure is a perspective view of the receptacle, showing my new design.

I claim:

The ornamental design for a receptacle for dispensing drinking straws, as shown.

FREDERICK W. SHEE.
